Specification of Letters Patent. Patented Mar. 21, 1916.

Application filed August 20, 1915. Serial No. 46,505.

To all whom it may concern:

Be it known that I, FRANK L. FISHER, a citizen of the United States, and a resident of Decatur, in the county of Mason, in the 5 State of Illinois, have invented certain new and useful Improvements in Telephone Pre-pay-Boxes for Use in Telephone Systems, of which the following is a specification.

This invention relates to a pre-pay box 10 which is suitable for use in a telephone system at stations where prepayment is demanded before use of the telephone is permitted.

The objects of this invention include the 15 obtaining of a device which may be used in party or individual line service, either in what is termed the automatic telephone, or in what is known as the manual common battery telephone, systems; and is illustrated 20 as installed in a two wire line system; the provision of a telephone pre-pay box, duplicates whereof can be installed on party lines in an automatic telephone system to establish, upon the removal of the receiver 25 from the hook provided therefor, a talking circuit, in a called station; and also in party lines in telephone systems which require a central operator, or an operator at a central station, to establish upon the like removal 30 of the receiver from its hook at a called station, a talking circuit with said central station, (said last named installation being accomplished by merely changing the wiring in said pre-pay box, as is hereinafter set 35 forth); the obtaining of a pre-pay box of the kind named which will necessitate the deposit of a predetermined coin at a calling station prior to the establishment of a talking circuit with a called station; the obtaining 40 of a prepay box of the kind named which, when a talking circuit has been obtained from a calling station, (subsequent to the removal of the receiver from its hook and the deposit of a coin in said box), with 45 a called station and said called station responds, will automatically deposit said coin in the safe provided therefor; and which when said last above named circuit has been established and said called station does not 50 respond, will automatically return said coin to a tray from which it can be obtained by the party calling, upon the return of the receiver at said calling station to its hook; the obtaining of a device whereby, when duplicate devices are installed on a party line and 55

a talking circuit has been established the same will not be broken or interrupted by the deposit of a coin in an additional and like pre-pay box on said party line; and a device by means of which, when a coin is deposited in said additional pre-pay box, as last above set forth, the party so depositing said coin is advised (by listening) that a circuit has already been established and said party line is busy, and thereupon upon the 60 return of his receiver to its hook, the coin so deposited by him in said additional pre-pay box will be automatically discharged from said box and returned to him.

Additional objects sought to be obtained 70 are: a pre-pay box which is simple in construction, readily understood, easily operated, not liable to get out of order, and economically made.

One of the important objects of the present invention is to so inter-relate and inter-connect the signaling and selector mechanism and the listening and talking mechanism, in a two line automatic telephone system, that it is imperative for a calling party 75 to deposit a coin in the coin box of the device before he can operate the signaling mechanism of his station for the purpose of actuating the selecting mechanism in the exchange to secure connection with a called 80 station: and another object, to which particular attention is directed, is to so accomplish the above recited results as to make it certain, when a coin has been deposited as above set forth, said signaling mechanism 85 operated and the connection established; the following results will automatically occur, to wit., if the receiver at the called station is not removed from its hook prior to the return of the receiver at the calling station to 90 its hook the coin will be returned to the party calling, and if the receiver at said called station is removed from its hook said coin will thereupon be deposited in the safe at the calling station; thus making it unnecessary for the party at the calling station to 95 perform any additional operation, either to deposit the coin in the coin safe or to recover it, so that control of the coin, after its deposit in the box, is automatically controlled.

In the drawings accompanying and forming a part of this specification, Figure 1 is a bottom plan view of the selective mechanism in a telephone stand of an automatic telephone system, adapted to be used in a 110

line equipped with pre-pay coin boxes embodying this invention. Fig. 2 illustrates a vertical section, on line 2—2 of Fig. 1, (on an enlarged scale) viewed in the direction indicated by the arrows; the parts shown being turned into an upright position. Fig. 3 is a vertical section, (enlarged from Figs. 1 and 2 and in an upright position), showing the base and standard of the telephone stand which is also illustrated in Figs. 1, 2 and 4. Fig. 4 illustrates a detail section, taken on line 4—4 of Fig. 1, viewed in the direction indicated by the arrows. Fig. 5 illustrates a vertical section of a pre-pay box embodying this invention, taken on line 5—5 of Fig. 6, viewed in the direction indicated by the arrows. Fig. 6 illustrates a vertical section, taken on line 6—6 of Fig. 5, viewed in the direction indicated by the arrows. Fig. 7 illustrates a horizontal section taken on line 7—7 of Fig. 5, viewed in the direction indicated by the arrows. Fig. 8 is an end view of the armature and coils which are illustrated in Fig. 7, showing the float arm or bar of the device, by broken lines. Fig. 9 illustrates an enlarged detail of said float arm, in side elevation, with the several coin actuated movable parts thereon in normal position. Fig. 10 illustrates a like view of said float arm as does Fig. 9, with the said movable parts in an actuated position, that is, as when a coin is on said float arm. Fig. 11 is a diagrammatic view of a pre-pay box embodying the invention, showing the wiring, posts, (or terminals), coils and movable parts arranged as a party telephone equipment installed in an automatic telephone system, and in a normal position, (being the position of said parts after a connection with an additional and like installed device), and of the several parts of an automatic telephone stand and the wiring thereof, with the receiver of said telephone assumed to be on its hook. Fig. 12, is a diagrammatic view of a telephone as installed in a telephone system requiring a central operator and equipped with devices embodying this invention, with the receiver assumed to be off its hook, and of a coin box embodying this invention, showing the wiring thereof as required when the same is installed in said central operator system, with the coin actuated parts in a normal position.

55 A reference character applied to designate a given part indicates said part throughout the several figures of the drawing, wherever the same appears.

1^a, 2^a, 3^a, 4^a, and 5^a, designate posts, or terminals, of a telephone instrument; and 1, 2, 3, 4, and 5, designate corresponding posts or terminals in a pre-pay coin box embodying this invention: 1 and 4 being what are termed the line posts in a two line system.

1^b, 2^b, 3^b, 4^b, and 5^b, are flexible wires, electrically connecting corresponding posts or terminals of the telephone instrument with those of the coin box.

W represents a pre-pay coin box.

X, X^a and X^b represent a coin run way and branches therefrom; one of said branches arranged to discharge into the coin safe of the device and the other into a tray in front of the said box; and Y, Z are line wires.

6 represents the base of a telephone standard; 7 the vertical tube forming the standard; 8 a lever fulcrumed at 9 to said standard, and 10 a vertical movable rod which is attached to lever 8 by pin or bolt 11. The lever 8 is known in the art, and hereinafter termed, the receiver hook.

12 is a representation of a spring on the lower end of rod 10, and 13 is insulating material. Spring 12 is adapted to yieldingly maintain rod 10 in a depressed position, but said spring is not of sufficient resiliency to hold said rod in said depressed position when the telephone receiver (14) is on said hook, (8).

15 represents a telephone transmitter; 16 a condenser; and 17 a bell.

18 represents a rotatable cam, and 19, 20, 21 and 22, respectively, spring contacts of the selecting mechanism of an automatic telephone. Spring contacts 20, 21 are illustrated as being placed on spring leaves which are integral, as is the usual construction.

The several elements W, X, X^a, X^b, and those numbered from 6 to 22, all inclusive, as also coin box W, and, of course, line wires Y and Z, are found in all automatic telephones of ordinary construction, which are installed in a two wire line; and are illustrated and described to enable me to easily show and describe the interconnection and interdependence of said parts with the device embodying my invention.

23, (Figs. 2, 3, 4, and 11) represents an electrical contact point. 24, 25, and 26, (in the above recited figures) and 27, 28 and 29, (Figs. 5, 7, 9, 10, 11, and 12) represent electrical contact points mounted on leaf springs, and are termed, in the art, spring contacts. Said leaf springs are electric conductors and are mounted on insulating material, (35).

In Figs 5 to 12, all inclusive, a pivoted arm or bar, which is hereinafter termed a float bar, is illustrated and designated by the numeral 30. 31 are the pivots on which float bar 30 turns, and 32 is an armature which is rigidly secured on said float bar. The several spring contacts 27, 28 and 29 are illustrated as mounted on float bar 30. 33 is a flat spring which is illustrated as secured to the upper side of float bar 30; 34 is a block or pin of insulating material which is inter-

posed between spring 33 and the leaf of spring contact 28, to transmit deflection of said spring 33, (by a coin on said float bar) to said spring contact. Spring 33 is normally in position with contacts 27 and 28 in electrical connection, but is not of sufficient resiliency to remain in said normal position when a coin is deposited on the float arm and against the free end thereof. When said spring 33 is in a raised position the spring contacts 27 and 28 in electrical connection, the contacts 28 and 29 are not in electrical connection. The free end of said spring 33 (and of float bar 30) projects into runway X, in position to receive (on said float bar) a coin deposited in said runway, and said coin, so deposited being received on said float bar and deflecting said spring 33, the electrical contact of contact points 27 and 28 is broken, and an electric contact between contact points 28 and 29 is made, (as is illustrated in Fig. 10).

Referring back to the telephone instrument, (Fig. 11), 36 illustrates an electric conductor from terminal 1^a to the leaf of spring contact 24; 37 a like conductor from terminal 2^a to spring contact 23; 38 a conductor from terminal 3^a to spring contacts 20 and 21; 39 a conductor from terminal 4^a to spring contact 19; 40 a conductor from terminal 5^a to spring contact 25. 41 a conductor from spring contact 26 to spring contact 22; 42 a conductor from spring contact 22 to telephone receiver 14; 43 a conductor from receiver 14 to telephone transmitter 15; and 44 a conductor from transmitter 15 to spring contacts 20, 21.

It will be observed that direct electric connection is made between contact 26 and receiver 14 by means of conductors 41 and 42; and also, direct connection is made between terminal 3^a and telephone transmitter 15, by means of conductors 44 and 38.

The line wires (Y, Z), are electrically connected to terminals 1 and 4; and terminal 1 is electrically connected to terminal 1^a by means of flexible conductor 1^b. In like manner terminals 2 and 2^a are electrically connected by means of conductor 2^b; 3^a and 4^a by conductor 4^b; and 5 and 5^a by 5^b.

In the coin box (see Figs. 5 and 7), 51 represents a permanent magnet; 52, 53 electro-magnetic coils; and 54, 55 the soft iron cores of said coils. Magnet 51 serves to magnetize cores 54, 55, when no current is flowing through coils 52, 53, (in the ordinary way), making the ends of said cores which are adjacent to armature 32 positive and the other ends negative. When a current is flowing through either of said coils in one direction the positive end of the core of the coil through which said current is flowing is increased; and when a current is flowing through said coils, or either

of them, in the opposite direction said permanent magnetism of the core is diminished; and if said oppositely flowing current is sufficient said end of the core is oppositely magnetized so as to energize it. 70

The float arm 30 and armature 32 are joined so that the position of said armature determines the position of the float arm, and 56 represents springs which yieldingly hold said armature in a neutral position, 75 which is its normal place, so that a coin deposited on the float arm will be retained thereon.

57 represents a resistance coil, (see Figs. 5, and 11). 80

58 is an electric conductor which is connected to terminal 2 and coil 53; and 59 a like conductor connected in like manner to terminal 3 and spring contact 28. 60 is a like conductor connecting terminal 4 and 85 spring contact 27; 61 a like conductor connecting terminal 5 and coil 52; 62 a conductor connecting the other end of coil 52 with one end of resistance coil 57; 63 a conductor connecting the other end of coil 57 with 90 spring contact 29; 64 a conductor connecting spring contact 29 with one end of coil 53; 65 a conductor connecting terminal 1 with condenser 16; 66 a conductor connecting condenser 16 with signaling device, (or ringer) 95 17; and 67 a conductor connecting signaling device 17 with terminal 4, (see Fig. 11).

When receiver 14 is on its hook, 8, (as in Fig. 11), and also when said receiver is off its hook, a closed circuit exists from one line wire to the other, in the coin box, this circuit being at all times unbroken, (being bridged across said line wires); and this circuit, which I term circuit No. 1, comprises:— 105

1. Terminal 1, (see Fig. 11), conductor 65, condenser 16, conductor 66, signaling device 17, conductor 67, and terminal 4. On taking receiver 8 off its hook, at what I call a calling station, a circuit is established 110 which I term circuit No. 2, and which comprises:—

2. Terminal 1, (see Fig. 11), conductor 1^b, terminal 1^a, conductor 36, spring contacts 24, 25, 26, conductors 41, 42, receiver 14, 115 conductor 43, transmitter 15, conductor 48, spring contacts 20, 19, conductor 39, terminal 4^a, conductor 4^b, and terminal 4. Assuming an effort be made to establish a circuit between the calling station and any other station, (which I call the called station), upon taking receiver 14 off its hook 8 and without the deposit of a coin in the pre-pay box, the following circuit is established, which I term circuit No. 3. 120

3. Terminal 4, (Fig. 11), conductor 60, spring contacts 27, 28, conductor 59, terminal 3, conductor 3^b, terminal 3^a, conductor 38, spring contacts 20 and 19, conductor 39, terminal 4^a, and conductor 4^b back to terminal 130

nal 4. This circuit being on one side of the line, only, that is, from terminal 4 over the several elements, as traced, back to said terminal 4, no impulse will be sent over the line 5 wires to the selective mechanism at the central station. Upon inserting a coin in runway X said coin, (68, Fig. 10), is deposited on the float bar 30, resting on and depressing spring 33, pin 34 and spring contact 28. 10 The electric connection between spring contacts 27 and 28, (illustrated in Figs. 9 and 11), is broken, (see Fig. 10), and the last above described circuit (3) is broken. This also cuts the collecting coil 52 and resistance 15 57 into the circuit, as follows,—

4. Terminal 1, (Fig. 11), conductor 1^b, terminal 1^a, conductor 36, spring contact 24, spring contact 25, (receiver 14 being off its hook 8), conductor 40, terminal 5^a, conductor 20 5^b, terminal 5, conductor 61, coil 52, conductor 62, resistance 57, conductor 63, spring contact 29, spring contact 28, conductor 59, terminal 3, conductor 3^b, terminal 3^a, conductor 38, spring contact 20, spring contact 25 19, conductor 39, terminal 4^a, conductor 4^b, and terminal 4. This circuit has a current flowing through it, but said current is in the wrong direction to energize coil 52, and coin 68 will, under these conditions, remain on 30 float bar 30 until the calling station has established a circuit with a called station, (hereinafter described) and until said called station is put on a talking circuit by the removal of the telephone receiver from its hook; whereupon the current is reversed, and coil 52 is thereby energized; and the coin is discharged by means of the float bar 35 30 being moved. The coin is thus, under the conditions named, automatically deposited in runway X^a and coin safe W. Upon the discharge of the coin from the float bar the electric connection between spring contacts 27 and 28 is restored, said spring contacts resuming the position which is illustrated in Figs. 9 and 11. If a party at a 40 called station should not lift or remove said receiver at said called station from its hook and the party at the calling station replaces the receiver at said calling station on its hook, this circuit, (4) is broken, by the 45 separating of spring contacts 24 and 25, as is illustrated in Fig. 11. The coil 53 is, at such time in condition to return the coin to the calling party; circuit which I will term 50 55 "5" being established, as follows,—

5. Terminal 1, (Fig. 11), conductor 1^b, terminal 1^a, conductor 36, the spring contact 24, contact 23, conductor 37, terminal 2^a, conductor 2^b, terminal 2, conductor 58, coil 60 53, conductor 64, spring contact 29, spring contact 28, conductor 59, terminal 3, conductor 3^b, terminal 3^a, conductor 38, spring contact 20, spring contact 19, conductor 39, terminal 4^a, conductor 4^b, and terminal 4.

65 While a call is being made, the required im-

pulses of the selective mechanism at the calling station are transmitted on the circuit which I will term circuit "6", which is,—

6. Terminal 1, (Fig. 11) conductor 1^b, terminal 1^a, conductor 36, spring contacts 24, 25, 26, conductor 41, spring contacts 22, 21, 20, 19, conductor 39, terminal 4^a, conductor 4^b, and terminal 4. During the time the selecting mechanism is not being operated at the calling station, to establish a circuit with a called station, (as last above set forth, and a coin being on the float bar), the receiver 14 and transmitter 15 are in series bridge across the coil 52, thereby acting as a shunt. This bridging circuit I term "7". 75 While said selecting mechanism is being operated the transmitter, receiver and coil 52 are "shorted out" through spring contacts 21, 22. Circuit "7" comprises,—

7. Terminal 1, (Fig. 11) conductor 1^b, 85 terminal 1^a, conductor 36, spring contacts 24, 25, 26, (receiver 14 being off of hook 8) conductors 41, 42, receiver 14, conductor 43, transmitter 15, conductor 44, spring contacts 20, 19, conductor 39, terminal 4^a, conductor 4^b, and terminal 4. The circuit which is bridged by 7 comprises what I term circuit 8, consisting of the following elements,—

8. Terminal 1, conductor 1^b to terminal 1^a, conductor 36, spring contacts 24, 25, conductor 40, terminal 5^a, conductor 5^b, terminal 5, conductor 61, coil 52, conductor 62, resistance 57, conductor 63, spring contacts 29, 28, conductor 59, terminal 3, conductor 3^b, terminal 3^a, conductor 38, spring contacts 20, 19, conductor 39, terminal 4^a, conductor 4^b, to terminal 4.

A talking circuit having been established between a calling and a called station, and while the same is being used, if a party at 105 an additional and duplicate station inserts a coin in the device, the coin so inserted will not be collected, because of so much current being taken for the first party's receiver and transmitter and also the receiver 110 and transmitter at said additional station; all of said instruments being across the line. Hence the established talking circuit would not be interfered with. Furthermore, if said party at said additional station upon finding (by listening) that the line is in use by 115 a talking circuit which has already been established thereupon replaces the receiver at said additional station upon its hook the coin inserted by him will be returned, as 120 there is only one receiver and transmitter across the line, and coil 53 operates regardless of the direction in which the current is flowing therethrough; and there being no resistance in the circuit which is established 125 by his hanging up said receiver there is a strong current flowing therethrough. This circuit is termed "9", and comprises—

9. Terminal 1, (Fig. 11), conductor 1^b, terminal 1^a, conductor 36, spring contacts 130

24, 23, conductor 37, terminal 2^a, conductor 2^b, terminal 2, conductor 58, coil 53, conductor 64, spring contacts 29, 28, (a coin being on bar 30), conductor 59, terminal 3, conductor 3^b, terminal 3^a (Fig. 13), conductor 38, spring contacts 20, 19, conductor 39, terminal 4^a, conductor 4^b, and terminal 4.

In the modified wiring which is illustrated in Fig. 12, which is a diagram of the prepay box installed in a common battery (central operator) telephone system, the line wires Y and Z are electrically connected to terminals 2 and 4. Terminal 5 is grounded, and is also connected to spring contact 28 by conductor 60^a. Terminal 1 is electrically connected to coil 52 by conductor 61^a. Terminal 3 is connected to coil 53 by conductor 59^a. Coils 52 and 53 are connected to spring contact 29 by conductors 62^a and 64, respectively. Terminals 1, 2, 3 and 4, are connected to terminals 1^a, 2^a, 3^a and 4^a, of the telephone instruments by flexible conductors 1^b, 2^b, 3^b and 4^b, respectively. Terminal 1^a is electrically connected to spring contact 25, by means of conductor 45; terminal 2^a is electrically connected to spring contact 24 by conductor 46; terminal 3^a to spring contact 23 by conductor 47; 4^a to transmitter 15, by conductor 48; and transmitter 15 is connected to the receiver by conductor 49; and said receiver (14) is connected to spring contact 26 by conductor 50. The terminal 2^a is electrically connected to the ringer 17 by conductor 67^a; ringer 17 is connected to condenser 16 by conductor 66; and said condenser to terminal 4^a by conductor 65^a.

In the construction which is illustrated by Figs. 1 to 11 all inclusive, the signaling means are inoperative until a coin is deposited on the float arm, because until said coin is so deposited, (with the receiver off the hook and said hook raised) said signaling mechanism is an element of what is hereinbefore designated as circuit No. 3; and upon the deposit of a coin on the float arm of the device circuit No. 4 is established, with the signaling mechanism an element therein, and in operative condition; while in the modified construction or installation which is illustrated in Fig. 12 the signaling means, (including the ground from terminal 5) are rendered inoperative by being open at spring contacts 29 and 28, until a coin is deposited on the float arm. When a coin is so deposited spring contacts 29 and 28 are closed and a circuit is made which includes the ground, terminal 5, conductor 60^a, said contacts (28, 29), conductor 62^a, coil 52, conductor 61^a and terminal 1. This circuit I term circuit No. 9.

It will be observed on referring to Fig. 12, that the conductor 62^a is electrically connected at its ends to spring contact 28 and

coil 52, while in the construction illustrated in diagram in Fig. 11, said spring contact 28, is electrically connected to said coil 52 by conductors 63 and 62, with the resistance coil interposed; and the omission of 70 said resistance coil from said Fig. 12 is because of the fact that the operation is the same whether said resistance coil is present or absent; hence, in wiring the device for use as in said Fig. 12 the party making the 75 installation may connect said spring contact 28 and said coil 52 in either manner.

Attention is directed to Fig. 11, where it will be observed that with a coin on spring bar 33 (contacts 27 and 28 being thereby 80 broken and contacts 28, 29 being made) the circuit which has been designated No. 4 is established, and the direction of flow of current therethrough is determined by the receiver hooks at the calling and the called 85 station. When the receiver hook at the calling station is up and the one at the called station is down the current through coil 52 diminishes the magnetism of the core of said coil; but, owing to the resistance coil 90 57 being in said circuit the core is not oppositely energized. When, under the last named conditions, the receiver hook at the called station is raised the flow of current through coil 52 and resistance coil 57, is reversed, and the magnetism of the core of 95 said coil 52 is increased, and operatively energized, to move the armature 32 and float arm 30 to discharge the coin on the float arm into the safe W of the coin box. 100

I claim:—

1. In a telephone system, the combination of a plurality of talking and listening instrumentalities each thereof comprising a movable receiver hook, signaling means, said 105 instrumentalities and means adapted to form elements in a calling and a called sub-station, a prepay box, a float arm and a plurality of coils to control a coin on said float arm positioned in said prepay box, an intercommunication between the float arm and the signaling means for the purpose of maintaining the latter inoperative until a coin is supported by the float arm, and interconnections between the float arm and the 110 coils for the purpose of making said coils, when a coin is on said float arm, elements of circuits to make said signaling means 115 operative as a calling station, and co-operatively with the receiver hooks which are 120 positioned at said calling and at the called station to automatically control the disposition of said coin.

2. In a telephone system, the combination of talking and listening instrumentalities 125 comprising movable receiver hooks, signaling mechanism, said instrumentalities and mechanisms adapted to form elements in a calling and a called sub-station, a prepay box, a float arm and a plurality of coils to 130

control a coin on said float arm positioned in said box, an intercommunication between the float arm and the signaling mechanism for the purpose of shunting the latter until 5 a coin is supported by the float arm, and interconnections between the float arm and the coils for the purpose of making said coils, when a coin is on said float arm, elements of circuits to make said signaling mechanism 10 operative as a calling station and co-operatively with the receiver hooks which are positioned at said calling and at the called station to automatically control the disposition of said coin.

15 3. In a telephone system, the combination of talking and listening instrumentalities, a receiver hook and an additional receiver hook, signaling mechanism, said instrumentalities adapted to form a calling and a 20 called sub-station, a prepay box, a float arm and a plurality of coils to control a coin on said float arm positioned in said box, an in-called substation, a prepay box, a float arm and the signaling mechanism for the purpose of 25 shunting the latter until a coin is supported by the float arm, and interconnections between the float arm, the receiver hooks, and the coils for the purpose of making said receiver hooks and said coils, when a coin is 30 on said float arm, (and thereby said substation made a calling station), elements of circuits to control the disposition of said coin, and arranged so that the actuating one of said circuits is determined by the position of said receiver hook at the calling and 35 called stations.

4. In a telephone system, the combination of talking and listening instrumentalities, signaling mechanism, a receiver hook, a pre-pay box, a float arm and a plurality of coils to control a coin on said float arm, in said pre-pay box, one of said coils being a resistance coil, an intercommunication between the float arm and the signaling mechanism 45 for the purpose of shunting the latter until a coin is supported by the float arm, and interconnections between the float arm and the coils for the purpose of making said coils, when a coin is on said float arm, elements 50 of circuits to control the disposition of said coin, said control obtained by a plurality of circuits which are determined by the position of said receiver hook, and said resistance coil and an additional one of said coils forming elements in the one of said circuits which is made when the receiver hook at 55 the raised.

5. In a telephone system, the combination of talking and listening instrumentalities, 60 signaling mechanism, a receiver hook, a pre-pay box, a float arm and a plurality of coils to control a coin on said float arm, in said pre-pay box, an intercommunication between the float arm and the signaling mechanism for the purpose of shunting the latter 65

until a coin is supported by the float arm, to make a calling station thereof, selective mechanism, additional talking and listening instrumentalities adapted to form a called station and an additional receiver hook 70 thereto, an interconnection between the signaling and the selective mechanisms and between the selective mechanism and said additional talking and listening instrumentalities, and interconnections between the float arm and the coils for the purpose of making said coils, when a coin is on said float arm, elements of circuits to automatically control the disposition of said coin, and said control obtained by a plurality of circuits 80 which are determined by the position of said receiver hooks at said calling and a called station.

6. In a telephone system, the combination of talking and listening instrumentalities, 85 signaling mechanism, a receiver hook, a pre-pay box, a float arm and a plurality of coils to control coin on said float arm, one of said coils being a resistance coil, an intercommunication between the float arm and the signaling mechanism for the purpose of shunting the latter until a coin is supported by the float arm, selective mechanism, additional talking and listening instrumentalities and an additional receiver hook, an interconnection between the signaling and the selective mechanisms and between the selective mechanism and said additional talking and listening instrumentalities, and interconnections between the float arms and the 90 coils for the purpose of making said coils, when a coin is on said float arm, elements of circuits to control the disposition of said coin, and said control being effected by disposing circuits which are determined by the 95 position of said receiver hooks, said resistance coil and an additional one of the coils forming elements in the one of said circuits which is made when the receiver hook at the first named talking and listening instrumentalities is raised, said last named circuit remaining unbroken while a coin is on said float arm.

7. In a telephone system, the combination of talking and listening instrumentalities, 115 signaling mechanism, a receiver hook, a pre-pay box, line terminals, a float arm in said pre-pay box, a coin retainer on said float arm, spring contacts and a mechanical connection between said contacts also mounted 120 on said float arm, an interconnection between said contacts and the signaling mechanism for the purpose of shunting the latter until a coin is supported by said coin retainer to make a calling station thereof, additional 125 talking and listening instrumentalities and an additional receiver hook adapted to form a called station, a polarized relay for said float arm and a resistance coil, said relay and resistance coil arranged for increasing the 130

magnetic force of the core of said relay when a current is flowing through the coil thereof and through said resistance coil in one direction to actuate the float arm into 5 position for collecting a coin on the retainer of the float arm, and for lessening the magnetic force of said core, but not to energize it to actuate the float arm when a current is flowing in the other direction through said 10 relay and resistance coils, interconnections between said coils and spring contacts and the line terminals for obtaining a flow of said current in one direction when the calling station receiver hook is raised, and a 15 flow of said current in the other direction

when both of said receiver hooks are raised, and an additional polarized relay for actuating the float arm to throw the same into position for returning a coin on said retainer when a current is flowing therethrough in 20 either direction, the circuit in which said last named relay is an element being made by a coin on the retainer of the float arm with the calling station hook receiver being down.

FRANK L. FISHER.

In the presence of—

CHARLES TURNER BROWN,
E. A. WINCHELL,
